UNITED STATES PATENT OFFICE.

VALENTINE BLANK AND THOMAS J. ANTHONY, OF SPRINGFIELD, OHIO.

DEVICE FOR OPERATING WINDOW-SHADES.

SPECIFICATION forming part of Letters Patent No. 295,901, dated April 1, 1884.

Application filed January 14, 1884. (No model.)

To all whom it may concern:

Be it known that we, VALENTINE BLANK and THOMAS J. ANTHONY, both citizens of the United States of America, residing at Springfield, in the county of Clark and State of Ohio, have jointly invented certain new and useful Improvements in Devices for Operating Window-Shades, of which the following is a specification, reference being had therein to the accompanying drawings.

Our invention relates to devices for operating window-shades; and it consists of a metal rod or bar extending across the window and down one side of the casing of the same, through a box-formed guideway fastened to the face of the casing. The vertical limb of the bar is notched on one side at different points, and a spring-dog within the guideway engages with the notches in adjusting the bar at the various heights required. The window-shade roller is pivoted at either end to the bar just below the horizontal limb of the same, the end being turned downward a short distance to give room for the bearing thereon and for the operation 25 of the roller. At each end of the roller is a toothed pinion loosely pivoted thereon, which engages with a toothed rack on the casing or window-frame. The pinions are supported and guided by sliding brackets or keepers, 30 which extend around the rack-bars, and the journals of the roller upon which the pinions turn, at each end, extend through the front projecting ears of these keepers into staples in the carrier-bar.

Figure 1 is an isometric view of a window to which our improved device for operating the window-shade shown therein is applied. Fig. 2 is an enlarged view of the box-formed guideway through which the vertical limb of 40 the L-shaped bar to which the shade is attached is operated. Fig. 3 shows the end of the rack-bar and the sliding bracket or keeper which is operated over the same.

A is the window; B, the shade operating over the same. The shade here shown is of the ordinary kind, which is wound and unwound upon its roller by means of a cord. A spring shade-roller can, however, be used with our device, the object of which is to lower the shade from the top as well as to elevate it from the bottom of the window, both for the pur-

pose of ventilation and to let light into the room where the window may be located. On either side of the window are secured the long-toothed racks b. They are bent at an angle 55 downward and outward (in line with the body of the same) at their ends, so as to raise them sufficiently from the face of the window casing or frame, to which it is attached, to allow the brackets k, which extend around under the 60 rack-bars, to slide freely over them.

By reference to Figs. 1 and 3 the position of the sliding bracket with relation to the rack can be seen. The brackets k are U-shaped, and straddle the rack-bars from the under 65 side of the latter. The pinions c c, being loosely pivoted upon the journals of the roller a², between the two ears of the brackets, are kept in constant engagement with the teeth of the racks on either side of the window. The 70 ends of the journals d, after passing through each of the brackets k, are held by staples l, secured to the front of the shade-carrier bar D, which latter is operated to lower and also to raise the shade-roller with its attached 75 shade B. The bar D, which is shown in Fig. 1, is shaped like an inverted L, with the horizontal limb a extending across the window. The left end of limb a is turned at an angle 80 downward about three inches from its extreme end, and one of the staples l is fixed in this part, and opposite to this on the vertical limb a³, just below the angle, is the other staple, forming the two bearings for the roller a². The vertical limb a³ (seen on the right of the 85 window) of the bar D is held in and operated through a box-shaped guideway, b', screwed to the casing or frame of the window on one side, and the shade-roller is elevated and let down by means of this part of the bar D, a 90 knob, c', on the lower end of the limb a³ being used to manipulate it.

To provide for windows of different widths, the horizontal limb a, below which the shade-roller is pivoted, is made in two parts, onelapping upon the other. Each part is provided with a loop, e² and e³, and thumb-screw e⁴, to retain the two parts in proper relation to each other and to allow of their adjustment. The limb a³ of the carrier D is provided on one edge 95 with notches i i i, which are engaged by a dog, e, (seen in the view Fig. 2,) within the guide. 100

way b' . This dog is formed on the stem of the knob a' , (seen on the front of the guideway,) which extends through the plates of the same and is pivoted therein. A flatspring, d , presses 5 against the side of the dog, which latter automatically engages the notches i when the bar D is pushed upward. The notches i are sloped in from below to facilitate the operation of the dog, which latter is kept in engagement with 10 the edge of limb a^2 as the shade is raised or lowered. A small spiral spring, s , is introduced as bearing against the end of spring d . Either or both these springs may be used. The vertical limb a^2 slides freely up and down 15 through the opening f , (seen in the guideway b' ,) this opening being shaped to fit the bar, as shown in Fig. 2. As the shade is raised or lowered by means of the carrier-bar D , the loose pinions c travel over their respective 20 racks b b on each side of the window, carrying the shade-roller a^2 (with its shade B) in a true horizontal line. The shade-roller can be shifted up or down with the shade rolled up or unrolled, and the latter operated from any point 25 where the roller may be either by means of a cord or spring. In using a cord to operate the shade the lower part can be looped over the knob e' on the lower end of the bar D .

We claim as our invention—

30 1. A device for operating window-shades, consisting of an (inverted) L-shaped bar, extending across the window and down one side of the same, and having the shade roller pivoted thereto, said roller being provided with a toothed pinion loosely pivoted upon its journals at either end, which engage with vertical toothed racks on the window-frame as the shade is raised and lowered by said bar, said pinions being held in engagement by means of brackets, through which said racks extend, said brackets being adapted to slide over the rack-bars when the shade is raised and lowered by 35 said bar, substantially as set forth.

2. In a device for operating window-shades, the L-shaped bar D , having the horizontal arm 45 a , extending across the window, and means for adjusting the length of said arm, and the vertical limb a^2 , provided with notches i therein, the shade-roller a^2 , pivoted in bearings in said bar D upon either side of the window, and 50 having the loose pinions c upon its journals, the brackets or keepers k , through which the journals of said roller extend, the vertical toothed racks b , said brackets inclosing said pinions and racks, and adapted to slide freely 55 over the latter, (when the shade is operated,) and the guideway b' , provided with the dog e , and means for operating the same, whereby it is engaged with the notches i in bar D when the shade is raised or lowered by means of the 60 latter, substantially as set forth.

3. In a device for operating window-shades, a shade-roller provided with pinions loosely pivoted upon its journals, toothed racks with which said pinions engage on either side of 65 the window-frame, brackets through which the journals of said roller extend inclosing the racks, and adapted to slide over the same and to hold the pinions of the roller in engagement therewith, and a carrier-bar, of L shape, 70 extending across the window and down one side of the same, said roller being pivoted to said carrier-bar upon either side of the window, and a guideway through which the vertical limb of the carrier-bar extends, having a 75 spring-dog adapted to engage with notches in the vertical limb of the carrier-bar in raising and lowering the shade by means of the latter, as set forth.

In testimony whereof we affix our signatures 80 in presence of two witnesses.

VALENTINE BLANK.
THOMAS J. ANTHONY.
